UNITED STATES PATENT OFFICE.

DAVID G. DEE, OF ROCHESTER, NEW YORK, ASSIGNOR, BY MESNE ASSIGNMENTS, TO
ROCHESTER H. ROGERS, OF ROCHESTER, NEW YORK.

FIRE-ALARM SYSTEM FOR TELEPHONE-EXCHANGES USING LINE-DISTRIBUTERS.

1,233,037.

Specification of Letters Patent. Patented July 10, 1917.

Application filed February 25, 1914. Serial No. 820,951.

To all whom it may concern:

Be it known that I, DAVID G. DEE, of Rochester, in the county of Monroe and State of New York, have invented certain new and useful Improvements in Fire-Alarm Systems for Telephone-Exchanges Using Line-Distributors; and I do hereby declare the following to be a full, clear, and exact description of the same, reference being had to the accompanying drawings, forming a part of this specification, and to the reference-numerals marked thereon.

My present invention has for its object to provide a fire alarm call box and a circuit system to be used in conjunction therewith for the transmitting of fire alarm signals over subscribers' telephone lines which are part of, or operate in conjunction with, the so called semi-automatic, auto-manual and any other system in which in-coming calls on a plurality of subscribers' circuits are distributed by automatic switches to an idle trunk of a group of trunk circuits. To these and other ends the invention consists in certain improvements and combinations of parts, all as will be hereinafter more fully described, the novel features being pointed out in the claims at the end of the specification.

In the drawings:

The figure is a diagrammatic illustration showing mechanism illustrating one embodiment of my present invention.

My present invention has for its object to extend the usefulness and render practical the use of fire alarm signal boxes which despatch code signals when such boxes are applied to semi-automatic, auto-manual or other telephone systems in which the calls initiated in a group of subscribers' circuits are distributed over a smaller number of trunk circuits. This distribution is accomplished by means of automatic switches which are set into action upon the initiation of an incoming call, and so far as I am aware these switching mechanisms which are in use at this time require, as a common feature, that the line circuit shall be retained in a closed condition. It is because of this requirement that the present type of signaling mechanism which depends upon the breaking of the circuit to despatch the code signal is unserviceable. Briefly stated, my invention consists in bridging the signaling contact by a high resistance element and pro-

viding in conjunction therewith a circuit comprising relatively high and low resistance relays, the former being employed for holding the circuit of the release magnet of the connector switch open during the transmission of the alarm signal impulses, and the latter (the low resistance relay) operating as a repeater for transmitting the current impulses over the fire alarm circuit.

In the illustration I have shown a fire alarm box mechanism, indicated generally by A, comprising the code wheel A' and a revoluble cam A², which parts, it will be understood, are mounted for simultaneous rotation and are adapted to be driven by any suitable mechanism, preferably by a clock-train, illustration of which has been omitted. During the rotation of the code wheel A' the contact point a is vibrated into and out of engagement with the spring b when the laterally projecting finger a' attached to it drops into the notches between the teeth of the wheel A'. The spring b normally engages the spring c and is held in contact therewith by an insulated pin c' on a pivoted rock arm A³ which is released by the movement of the cam member A² when the box mechanism is set into operation. The latter also is provided with a set of contacts d and e which are normally separated, the latter being held out of engagement with the former by the stud e' on the arm A³. The telephone subscriber's instrument circuit comprises the line wires 1 and 2, the first being connected by the wire 1^a to the spring c, while the second extends beyond the terminals of the box, as indicated by 2^b, to the central office switches, although within the box mechanism said wire 2 is tied to the contact a by the lead 2^a. Leading from the wire 2 is the branch 1^d connected to one terminal of the high resistance spool D, of approximately 3500 ohms, the other terminal of which is connected by the wire e' to the contact spring e. It will be noted that the contact springs d and b are connected by the wire d' so that the resistance D, which is normally cut out of the circuit will be bridged across the line wires 1^b and 2^b as soon as the box mechanism begins its cycle of operation.

As previously mentioned, the call distributing mechanism operates to automatically connect one of a large number of lines, for instance, a group of one hundred subscrib-

ers' instrument circuits, to one idle trunk of a possible total number of ten trunks when the call is received. This mechanism is necessarily complicated both in structure and operation and as it forms no part of this invention and performs its usual function I have merely indicated it generally as comprising a pair of wipers 3 and 4 or other form of contacts, which are adapted to select the terminals of an idle trunk, which, when actuated by suitable mechanism, such as that disclosed in the Frank Newforth Jr. Patent No. 1,078,690, granted November 18, 1913, are retained in the actuated position by a trunk holding relay employed to prevent the disengagement of the wipers while it is retained in energized condition, but permitting their release when it is deenergized. This trunk holding relay is indicated by 5 and is shown arranged in the circuit composed of the wires 6 and 7 in which is interposed a battery X and a pair of contacts 8 and 9.

The trunks over which the calls are distributed in some instances to the central office from outlying stations and in other instances to the different operators' stations on the switchboard, comprise the wires 3^a and 4^a, the former terminating in the sleeve contact 3^b and the latter ending in the tip contact spring 4^b of a switchboard jack with which coöperates the plug of the fire alarm cord circuit comprising a tip 10 and sleeve 11. The trunk circuit is provided with a closed branch containing the high resistance relay 12 which serves to hold the contacts 8 and 9 together to prevent the release of the connector switch. This branch of the trunk comprises the wire i leading from the wire 3^a to one terminal of the coil of relay 12, the other extremity of the latter being connected by the wires h' and h to battery X², from which leads the wire g to a back contact f on the spring 4^b. From this it will be seen that when the subscriber's circuit is closed and the connector switch has picked up the idle trunk it is allowed to remain in this operated position while the subscriber's circuit is in operation. The fire alarm cord circuit comprises a low resistance relay 13 which may be connected in multiple with the high resistance 12 and employed to control the contacts 14 and 15 of the outgoing fire alarm circuit, shown as comprising the wires 16 and 17 in which are interposed the battery X' and the fire alarm signaling and recording mechanism F. The cord circuit is arranged as follows: The wire h is connected by wire h² to one terminal of the coil 13, the circuit being completed over the wire j leading to the sleeve contact 11 of the switchboard plug. The tip contact 10 of said plug is connected to the positive side of the battery X² by the wire k in which is interposed a winding k'.

In describing the operation of the apparatus in detail, it will be understood that when the alarm mechanism is set into operation by the release of the clock train which drives the code wheel A' and the cam A² simultaneously, the cam wheel first releases the lever A³ before the first notch in the code wheel relieves the tension on the finger a' and the spring a, consequently the latter is engaged by the spring b. The code wheel A' makes a plurality of complete revolutions for every complete revolution of the cam wheel A². The closing of the contacts a and b bridges the subscriber's telephone set and closes the line with the result that the call distributing switch is actuated to seize an idle trunk, current flowing over the circuit thus established as follows: battery X², wire g, contact f, spring 4^b, wire 4^a, wiper 4, wire 1^b, springs b and a, wires 2^a and 2^b, wiper 3, wires 3^a i, coil of relay 12, wires h', h to battery X². The energizing of the relay 12 holds the contacts 8 and 9 of the line switch releasing circuit closed so that the idle trunk seized by the wipers 3 and 4 will be held during the pulsations occurring in the subscriber's circuit, due to the transmitting of the fire alarm signal impulses. The rotation of the code wheel A' permits the contact spring a to be disengaged from the spring b each time one of the teeth or notches of the wheel passes the finger a'. There is a second bridge on this circuit comprising the wire 1^a, the high resistance D, wire e', spring e, spring d, wire d', which is also closed to include in the telephone circuit a high resistance during the opening and closing of the shunt springs a and b. By this time, the plug of the fire alarm cord circuit has been inserted in a subscriber's jack and impulses which occur therein are transmitted over the following circuit: battery X², resistance k', wire k, tip contact 10, spring 4^b, wire 4^a, wiper 4, wire 1^b, springs b, a, wires 2^a, 2^b, wiper 3, wire 3^a, sleeve contact spring 3^b, contact 11, wire j, relay coil 13, wires h², h to battery X². With each variation of the potential of the current in the above circuit occurring upon the separation of the contacts a and b, a corresponding movement of the armature of the low wound relay 13 is effected to close and open the contacts 14 and 15 by means of which the code signal is repeated over the fire alarm circuit and recorded by the apparatus F. The relay 12 is not deenergized by this varying of the potential of the subscriber's line circuit as it is of high resistance and delicately adjusted. The relay 13 is of low resistance and does not remain operated when the subscriber's telephone line circuit is closed only through the high resistance shunt D. The relay 13, therefore, operates in unison with the making and breaking of the springs a and b,

but the relay 12 remains energized, preventing the release of the trunk.

I claim as my invention:

1. The combination with a circuit, an alarm mechanism connected thereto and arranged to send impulses of current thereto, a telephone set connected to said circuit, contacts under the control of said alarm mechanism through which the telephone set is connected to the main circuit and by means of which the telephone set is disconnected from said circuit, a high resistance arranged to be thrown into the circuit between the impulses aforesaid, maintaining the circuit energized and closed, and relays, one of said relays being operable during the impulses and the other of said relays being operative between the impulses.
2. The combination with a circuit, an alarm mechanism connected thereto and arranged to send impulses of current thereto, a telephone set connected to said circuit, contacts under the control of said alarm mechanism through which the telephone set is connected to the main circuit and by means of which the telephone set is disconnected from said circuit, a high resistance arranged to be thrown into the circuit between the impulses aforesaid, maintaining the circuit energized and closed, an alarm circuit arranged to be connected to said main circuit, and switching mechanism adapted to disconnect said alarm circuit from said main circuit when the latter is opened.
3. The combination with a circuit, an alarm mechanism connected thereto and arranged to send impulses of current thereto, a telephone set connected to said circuit, contacts under the control of said alarm mechanism through which the telephone set is connected to the main circuit and by means of which the telephone set is disconnected from said circuit, a high resistance arranged to be thrown into the circuit between the impulses aforesaid, maintaining the circuit energized and closed, an alarm circuit arranged to be connected to said circuit and two relays, one operable during the impulses to close said alarm circuit, and the other operable between impulses and when the circuit is closed, by the high resistance aforesaid to lock said switch mechanism from operation.
4. The combination with an automatic switching mechanism adapted to connect one of a plurality of subscribers' lines to another line upon the closing of a subscriber's line and also to automatically restore to its normal position upon the opening of the subscriber's line, of an alarm mechanism on said line adapted to take possession thereof and close the same to cause the operation of said switching mechanism, and despatch impulses over the line by opening and closing the same, and means associated with

said alarm mechanism for maintaining the line closed upon the opening thereof by said alarm mechanism.

5. The combination with a subscriber's line circuit, of an automatic switching mechanism adapted to connect said line circuit to another circuit upon the closing of the line circuit and to restore to its normal position, to disconnect said circuits upon the opening of said line circuit, of an alarm mechanism bridged across said line circuit provided with contacts to close and open said circuit, and a resistance associated with said alarm mechanism for maintaining the line circuit closed when the contacts aforesaid are open.

6. The combination with a subscriber's line circuit, of an automatic switching mechanism adapted to connect said line circuit to another circuit upon the closing thereof and to restore to its normal position upon the opening of said line circuit, a resistance, and an alarm mechanism arranged to simultaneously bridge said resistance across the circuit and close the latter.

7. The combination with a subscriber's line circuit, of an automatic switching mechanism adapted to connect said line circuit to another circuit upon the closing of the former and restore to its normal position upon the opening thereof, a resistance, an alarm mechanism, and normally open contacts under the control of the alarm mechanism for bridging said resistance across the line circuit.

8. The combination with a subscriber's line circuit, of an automatic switching mechanism adapted to connect said line circuit to another circuit upon the closing of the former and restore to its normal position upon the opening thereof, a resistance, an alarm mechanism, and normally open contacts under the control of the alarm mechanism for bridging said resistance across the line circuit to normally close said line circuit during the operation of said alarm mechanism.

9. The combination with a subscriber's line circuit, of an automatic switching mechanism adapted to connect said line circuit to another circuit upon the closing of the former and restore to its normal position upon the opening thereof, a resistance, an alarm mechanism, and two sets of contacts under the control of said alarm mechanism for simultaneously bridging the resistance across the line circuit and closing the same.

10. The combination with a subscriber's line circuit, of an automatic switching mechanism adapted to connect said line circuit to another circuit upon the closing of the former and restore to its normal position upon the opening thereof, a resistance, an alarm mechanism, a set of normally open contacts in connection with said resistance, a set of normally open contacts connecting

one with each side of the line circuit, and means under the control of the alarm mechanism for closing the resistance contacts to bridge the resistance across the line circuit and to close and open the contacts connected with the line circuit.

11. The combination with a subscriber's line circuit, of an automatic switching mechanism adapted to connect said line circuit 10 to another circuit upon the closing of the former and restore to its normal position upon the opening thereof, a resistance, an alarm mechanism, means under the control of said alarm mechanism for bridging the 15 resistance across the line circuit to maintain said circuit closed, and further means likewise under the control of the alarm mechanism for short circuiting said resistance.

12. The combination with a subscriber's 20 line circuit, of an automatic switching mechanism adapted to connect said line circuit to another circuit upon the closing of the former and restore to its normal position upon the opening thereof, a resistance, an alarm mechanism, means under the control of said alarm mechanism for bridging the resistance across the line circuit to maintain said circuit closed during the entire operation of said mechanism, and further means 25 likewise under the control of the alarm mechanism for periodically short circuiting said resistance.

13. The combination with a subscriber's 30 line circuit, of an automatic switching mechanism adapted to connect said line circuit to another circuit upon the closing of the former and restore to its normal position upon the opening thereof, a resistance, an alarm mechanism, means under the control 35 of said alarm mechanism for bridging the resistance across the line circuit to maintain said circuit closed during the entire operation of said mechanism, and further means likewise under the control of the 40 alarm mechanism for periodically short circuiting said resistance and simultaneously closing the line circuit.

14. In an alarm apparatus, the combination 45 with a subscriber's circuit, a central exchange and automatic switching mechanism associated with said circuit, of means for rendering said mechanism unresponsive to impulses of current transmitted over said circuit comprising an electromagnet arranged to restrain the action of the switch 50 having a circuit, an alarm circuit provided with alarm apparatus, an operating circuit having relatively high and low resistance relays therein, the former arranged to control the restraining magnet circuit and the latter to control the alarm circuit and means for transmitting impulses of current over the subscriber's circuit and the connected operating circuit.

65 15. The combination with a subscriber's

telephone line circuit, a central exchange, an operating circuit adapted to be connected to the subscriber's line having relatively high and low resistance relays therein and automatic switching mechanism employed for establishing a portion of the connection 70 existing between the line and operating circuits which is normally susceptible to the action of current impulses on the line, of an electromagnet co-operating with said mechanism to render it unresponsive to such impulses having a circuit which is controlled by the high resistance relay during the action of the low resistance relay, an alarm circuit controlled by the latter and means for producing current impulses on the line.

16. The combination with a subscriber's 75 telephone line circuit, a central exchange, a line switch serving to automatically connect the subscriber's circuit to a trunk leading to the central exchange which is normally capable of automatically restoring itself to disconnect the line when the latter is opened, and an alarm operating circuit at the central 80 office adapted to be connected to the line having relatively high and low resistance relays, of an electro-magnet arranged to restrain the release operation of the switch having a circuit controlled by the high resistance relay, an alarm circuit having alarm 85 mechanism therein arranged to be controlled by the low resistance relay and means for despatching impulses of current over the connected line and alarm operating circuits.

17. The combination with a subscriber's 90 telephone line circuit, a central exchange, an alarm operating circuit adapted to be connected to the line circuit having relatively high and low resistance relays therein, and an impulse despatching mechanism arranged to bridge a high resistance across the line circuit and to subsequently open and close the circuit within said bridge, of a switch serving to establish a portion of the 95 connection existing between the line and operating circuits which is susceptible to the action of current impulses on the line, an electromagnet for rendering said switch unresponsive to such impulses having a circuit controlled by the high resistance relay, and an alarm circuit controlled by the low resistance relay, the latter acting to cause current impulses on the line circuit to be 100 repeated on the alarm circuit.

18. The combination with a subscriber's 105 line circuit and telephone set, of a resistance, an alarm mechanism, means under the control of the alarm mechanism for cutting the telephone set from the line and simultaneously closing the line circuit, and means also under the control of the alarm mechanism for bridging the resistance across the line circuit.

19. The combination with a subscriber's 110

line circuit and telephone set, of a resistance, an alarm mechanism, means under the control of the alarm mechanism for cutting the telephone set from the line and simultaneously closing the line circuit and to further periodically open and close said line circuit, and means also under the control of the alarm mechanism for bridging the resistance across the line to maintain the same normally closed during the operation of the alarm mechanism.
